COMMUTATOR FINISHING MACHINE

Lora E. Poole, Anderson, Ind., assignor to General Motors Corporation, Detroit, Mich., a corporation of Delaware

Application July 5, 1935, Serial No. 29,855

16 Claims.

(Cl. 51—5)

This invention relates to commutator finishing machines and more particularly to a machine performing successive finishing operations on the commutator of an armature assembly.

5 It is one of the objects of the present invention successively to turn the polygonal commutator of an armature assembly into cylindrical shape and to smoothen the comparatively rough periphery of the turned commutator in order to obtain good 10 electrical contact between the commutator and a brush riding thereon and to reduce the wear of the latter to a minimum.

This object is accomplished by turning the polygonal circumference of the commutator into 15 cylindrical shape and thereafter stretching an abrasive strip such as emery paper partly around the periphery of the rapidly spinning commutator.

It is another object of the present invention 20 automatically to advance the abrasive strip sufficiently to compensate in fresh strip material that amount of abrasive which is persistently worn off during smoothening operations.

It is another object of the present invention to 25 provide for relative movement between the abrasive strip and the spinning commutator longitudinally of the latter not only to exhaust the abrasive but also to prevent the occurrence of annular ridges which are so conspicuous on cylindrical surfaces abraded by mere relative rotation 30 between said surface and the abrasive.

Further objects and advantages of the present invention will be apparent from the following description, reference being had to the accompanying drawings wherein a preferred embodiment 35 of the present invention is clearly shown.

In the drawings:

Fig. 1 is a perspective view of a machine embodying the present invention.

40 Fig. 2 is another perspective view of the machine, viewed from the rear thereof.

Fig. 3 is a fragmentary rear elevation of the machine.

45 Fig. 4 is a fragmentary plan view of the machine.

Fig. 5 is a section taken on the line 5—5 of Fig. 3.

50 Fig. 6 is a fragmentary section taken on the line 6—6 of Fig. 5.

Fig. 7 is a fragmentary, longitudinal section through the work support of the machine.

55 Fig. 8 is a section similar to that of Fig. 7, however, certain parts being shown in a different position of operation.

Fig. 9 is a section taken on the line 9—9 of Fig. 7.

Fig. 10 is an enlarged fragmentary section taken on the line 10—10 of Fig. 3.

Fig. 11 is a fragmentary section taken on the line 11—11 of Fig. 10.

Fig. 12 is a section taken on the line 12—12 of Fig. 10.

Fig. 13 is a fragmentary section taken on the line 13—13 of Fig. 10.

10 Figs. 14 to 16 inclusive illustrate certain electrical circuits for the motor drive of the work operated upon.

Fig. 17 is a cam chart representing the movement of certain structure of the machine.

15 Referring to the drawings, the reference numeral 20 designates the bed of a conventional lathe having longitudinal guide-ways 22 on which a transport 24 is slidable. Longitudinally ad-

justably mounted at one end of the lathe bed 20 is a tail-stock 26 and mounted on the other end thereof is an electric motor 28 which supports and drives a centrifugally operated chuck 30,

adapted to grip one end of the shaft 32 of an armature assembly 34, the other end of said 25 armature shaft 32 is journaled in the tail-stock 26.

The transport 24 is provided with guide-ways 36 supporting a slide 38 for movement at right angles to the direction of movement of the transport 24.

30 Mounted on this slide 38 is a tool 40 for turning the polygonal circumference of the commutator 42 of the armature 34 into cylindrical shape, and a device including a supply of abrasive, preferably emery paper 44, for smoothening the turned periphery of the commutator.

Suitably journaled in bearing brackets 46 at the rear of the machine is a shaft 48, carrying cams 35 for moving the transport 24 as well as the slide 38. The cam shaft 48 is driven by means of an electric motor 50 which is mounted in any suit-

able manner on the rear of the machine. A manually engageable clutch 52 is provided and adapted to cause or interrupt driving connection 40 between motor 50 and cam shaft 48. The clutch 52 is automatically disengaged after a completed 45

turning and smoothening operation of the machine. Such automatic disengagement of the clutch causes immediate braking of the chuck 46 driving motor 28 and subsequent stopping there-

of as will be described later.

50 With sole reference to Fig. 4 the operation of the machine is briefly as follows:

After proper mounting of an armature the transport 24 is caused to move to the left, where-

55 by the tool 40 moves longitudinally of the com-

mutator 42 while in cutting engagement therewith. Immediately upon arrival of tool 40 in the dot-and-dash position, the transport 24 returns into the full line position while remaining in cutting engagement with the commutator. Thereafter and while the transport 24 remains in the full line position, the slide 38 is caused to move in the direction of arrow 60, whereby the abrasive material 44 approaches the turned commutator periphery and is subsequently stretched around part of said periphery in the manner shown in dot-and-dash lines in Fig. 10. The transport 24 is then moved slightly to the left as shown in Fig. 4, sufficiently to contact the abrasive material with the entire length of the commutator. As soon as the abrasive strip reaches the left margin of the commutator, the transport 24 immediately reverses its direction of movement and returns to the full-line position, however with the abrasive strip still stretched around part of the commutator periphery. Thereafter, the slide 38 moves in the direction of arrow 62 into the full-line position, in which the tool 40 is in longitudinal cutting alignment with the commutator of a new armature to be deposited in the machine. This ends a complete cycle of operation of the machine.

Chuck and tail stock

Referring particularly to Figs. 1, 2 and 7 to 9 inclusive, the rotor shaft 70 of the electric motor 28 supports and drives the centrifugally operated chuck 38 as will be presently described. Mounted by means of a key 16 to one end of the rotor shaft 70 which extends beyond the motor 28 is a frame 74. Slidable in this hollow rotor shaft 70 is a sleeve 78 which is connected to a draw bar 80 by means of a nut 82. Interposed between a shoulder 84 of said sleeve and a retainer 86, secured at 88 to frame 74, is a compressed spring 90 which normally urges sleeve 78 and therewith drawbar 80 to the right as shown in Fig. 7. Pivotally mounted at 92 in opposite recesses 94 of frame 74 are levers 96 which carry weights 98, having arcuate slots 100 concentric of the pivot axes 92, through which pins 102 extend which are secured to the frame 74. The levers 96 are also provided with lugs 104 which extend through opposite slots 106 of the rotor shaft 70 and engage sleeve 78. Upon rotation of the rotor shaft 70, the weights 98 fly outwardly by centrifugal force, causing the lugs 104 of the weight carrying levers 96 to move sleeve 78 and therewith drawbar 80 to the left as shown in Fig. 8, i. e. against the compression of spring 90. After the rotor of the electric motor again comes to rest, spring 90 expands under its own compression, thereby causing the weights 98 to move into the position shown in Fig. 7 through intermediation of sleeve 78 and levers 96, as can be readily understood. The hollow rotor shaft 70 is at one end internally tapered and receives therein a sleeve 108 which is provided with an internally tapered, annular surface 110. Sleeve 108 is held in place by a dowel pin 112. Cooperating with the tapered surface 110 of sleeve 108 is the externally tapered portion 114 of a chuck 116 which is preferably split at three equi-angular intervals to provide gripping jaws 118. This chuck 116 is threadedly connected at 120 with an enlarged portion 122 of drawbar 80, slidable in the hollow rotor shaft 70. It can now be understood that while the rotor shaft 70 is at rest, the chuck 116 is in the extreme right end position shown in Fig. 7 and consequently is not gripping the armature shaft 32. However, upon rotation of said rotor shaft 70, the weights 98 fly outwardly by centrifugal force, causing movement of the chuck 116 from the position shown in Fig. 7 to that shown in Fig. 8, whereby the tapered surfaces 110, 114 of sleeve 108 and chuck 116, respectively, cooperate to force the jaws 118 into gripping engagement with the armature shaft 32.

The opposite end of the armature shaft 32 is suitably journaled in a ball bearing 122 which is carried by a reciprocable spindle 124 of any suitable tail stock 26. Since this tail stock does not form part of the present invention, no detailed description thereof is deemed necessary, it being sufficient to understand that manipulation of a hand lever 126 about an axis 128 into either one of two positions will cause movement of the tail stock spindle 124 into either the full-line or the dot-and-dash position shown in Fig. 7. To remove an armature from the tail stock and the chuck, the tail stock spindle 124 is withdrawn into the dot-and-dash position, and to deposit a new armature, the shaft 32 thereof is introduced into the chuck 116 and the tail stock spindle moved into the full line position in Fig. 7. To insure that a shoulder 130 of the armature shaft 32 is in abutment with the tail stock spindle, a plunger 132 in the enlarged portion 122 of drawbar 80 is normally urged by means of a compression spring 134 to the right as viewed in Fig. 7, engaging the adjacent end of the armature shaft and thus shifting the same to the right until such abutment occurs. Movement of plunger 132 is limited by means of an oblong slot 136 in said plunger and a pin 138, carried by the enlarged portion 122 of drawbar 80.

Turning tool

As best shown in Figs. 4 to 6 inclusive, the slide 38 provides guideways 140 for movement of a tool slide 142 at right angles to the armature shaft. This tool slide 142 is provided with a groove 144, receiving a T-bolt 146 which is carried by a tool block 148, having a machined rib 150 which is guided for movement parallel to the armature shaft in a narrow portion 152 of groove 144. By loosening the nut 154 of the T-bolt, the tool block 148 may be adjusted longitudinally of the armature shaft and locked in adjusted position by tightening nut 154. Located in an aperture 156 of said tool block is the cutting tool 40 which is secured therein in adjusted position by means of a clamping screw 158. Slide 38 is provided with lug 160 through which extends a screw 162, threaded into the tool slide 142 and provided with a collar 164. A shoulder 166 of screw 162 and the collar 164 straddle the lug 160, preventing longitudinal movement of the screw relative to the lug but permitting free rotation of said screw which is provided with a square head 168 for the application of a wrench or other suitable tool, thereby to adjust the position of the tool slide 142 on the guideways 140. It can now be understood that the cutting tool 40 can be adjusted longitudinally of and parallel to an armature in the machine.

Abrading device

Referring more particularly to Figs. 3 to 5 inclusive, and 10 to 13 inclusive, there are two parallel upright frames 170 mounted at 172 to the slide 38. Tie rods 174 maintain the frames 170 in spaced parallelism. Mounted in bushings 176 of the frames 170 are two parallel feed rolls 178. Cooperating with these feed rolls 178 are

companion rolls 178 which are journaled in externally square bushings 180, having opposite flanges 182 and riding in rectangular slots 184 of the frames 170. These companion rolls 178 have a non-metallic lining 186, preferably of bakelite or rubber, and are normally urged into engagement with the feed rolls 176 by compression springs 188 which act on the bushings 180 and are housed in retainer blocks 190, secured by screws 192 to the frames 170. The bushings 180 are provided with additional guide pins 194 which extend through suitable bores of the retainer blocks 190. One of the frames 170 pivotally supports at 196 a comparatively heavy lever 198, the forked portion 200 of which straddles a pivotally mounted roll 202. Extending from lever 198 is a pin 204 which in the lowermost position of roll 202 rests on top of one of the frames 170 as best shown in Fig. 5. Pivotally mounted at 206 to the same frame 170 which carries lever 198 are two guide rolls 208 which are parallel to the feed rolls 176, 178 and also to the weight roll 202. A suitable reel 210 is pivotally mounted at 212 to one of the frames 170 and contains a supply of abrasive strip material 44 such as emery paper of a selected grade. A strip 44a of emery paper is initially guided around the various rolls just described by drawing a strip of emery paper from the supply on the reel and feeding the same between the first pair of cooperating feeding rolls 176, 178, then around the weight roll 202 and over the guide rolls 208 and finally between the second pair of feed rolls 176, 178. Upon the earlier mentioned approach of the abrading device to the commutator, the strip portion 44b between the guide rolls 208 is caused to embrace part of the periphery of the commutator and the resulting stretching of the abrasive strip between the first pair of cooperating feed rolls 176, 178 and the nearest guide roll 208 causes the weight roll 202 as well as the lever 198 to be raised from the position shown in Fig. 10 in which the pin 204 of said lever 198 rests on one of the frames 170. It can therefore be understood that upon engagement of the abrasive strip portion 44b with a commutator periphery, the weight roll 202 tightens the entire strip portion situated to the left of both pairs of feed rolls 176, 178 in Fig. 10. It can likewise be understood that while the strip portion 44b is out of engagement with a commutator, the weight roll 202 is ineffective because the pin 204 of lever 198 then rests on top of one of the frames 170 and the strip 214 rather loosely embraces part of the periphery of said weight roll.

In order to compensate in fresh strip material that amount of abrasive which is worn off during smoothening operations, the feed rolls 176, 178 are intermittently indexed, thereby drawing fresh strip material from the supply and exhausted strip material away from the guide rolls 208 as will be presently described. Each pair of cooperating feed rolls 176, 178 is provided with meshing, identical gears 216. The gears 216 of the feed rolls 176 are both in mesh with another gear 218 which is mounted on a stub shaft 220, journaled in suitable sleeves 222 of the frames 170 and carrying at one end a ratchet disc 224 with which cooperates a pawl 226, normally urged into engagement with the ratchet disc by a spring urged plunger 228, carried by an arm 230 which is suitably journaled at 232 to the stub shaft 220. It has been already explained that the slide 38 has a definite motion at right angles to the armature in order to approach and withdraw the strip

portion 44b to and from a commutator periphery. This motion is utilized for the indexing of the feed rolls 176, 178 as will be presently explained. Mounted by screws 234 to the transport 24 is a bracket 236, having two spaced lugs 238, receiving set screws 240a and 240b which are in alignment with the pawl carrying arm 230. The set screw 240a is so adjusted that during the latter part of approaching movement of the abrading device to the commutator, the arm 230 strikes 10 said set screw 240a and is thereby slightly rotated counterclockwise, resulting in a jumping by the pawl 226 of one or more teeth of the ratchet disc 224. There is sufficient friction in the journal support of arm 230 to maintain the latter in 15 the position assumed after such slight counterclockwise rotation. During the latter part of retraction of the abrading device into the position shown in Fig. 5, arm 230 strikes the other set screw 240b and is thereby rotated clockwise until 20 said abrading device comes to rest in most retracted position. Such clockwise rotation of arm 230 results in an indexing of the ratchet disc 224 by the pawl 226 and may amount to the angular 25 distance between two or more consecutive ratchet teeth, depending upon the adjustment of set screw 240b. However, the indexing of the ratchet disc 224 can under no circumstances exceed the amount of counterclockwise rotation of arm 230 as caused by set screw 240a as can be readily understood. Rotation of the ratchet disc 224 is 30 transmitted to both pairs of cooperating feed rolls 176, 178 through intermediation of stub shaft 220, gear 218 and gears 216, resulting in a slight 35 advance of fresh strip material in the direction of arrow 242 in Fig. 10 and according withdrawal of exhausted strip material in the direction of arrow 246. It can now be understood that with each abrading operation, exhausted strip material is 40 automatically compensated by fresh strip material. In order initially to thread strip material between both pairs of cooperating feed rolls 176 and 178, one end of stub shaft 220 is suitably flattened at 250 for the appliance of a wrench or 45 thereby the feed rolls 176, 178 in the proper direction.

Movement of transport and slide

As already mentioned, a cam shaft 48 is mounted in the rear of the machine and carries certain cams for moving the transport as well as the slide. One of these cams is in the form of a cam groove 260 in a drum 262 which is mounted on shaft 48. Cooperating with this cam groove 260 is an anti-friction roller 264 (see also Fig. 5) 50 which is carried by a bracket 266, mounted by bolts 268 to the transport 24 which is retained on the guide ways 22 of the lathe bed by means of gib plates 210. Motion of the transport 24 for one complete cycle of operation of the machine is caused by one revolution of cam drum 262. In order to prevent a backing up of the cam drum after one complete revolution thereof, i. e. after disengagement of the earlier mentioned clutch 52, a pawl 272, pivotally mounted at 273 to the lathe bed, is adapted to engage the shoulder 274 of an arcuate plate 276 which is angularly adjustably mounted on the cam drum 262. Since the cam drum rotates normally clockwise as viewed in Fig. 70 5, it can be understood that the pawl 272 does not interfere with the normal rotation of said cam drum but merely prevents counterclockwise rotation thereof after one complete revolution in normal direction. Also mounted on shaft 48 is a 75

disc cam 278 which cooperates with an anti-friction roller 280 of an arm 282, pivotally mounted at 284 to a lug 286 of one of the bearing brackets 46. As best shown in Fig. 5, the other end of 5 arm 282 is part-cylindrical and received in a socket 287, provided by an angle 288 which is secured to slide 38 by screws 290. The transport 24 includes a transverse tie 292 on which the slide 38 is movable in the earlier mentioned guideways 36. 10 Extending over the greater length of said tie 292 is a bore 296 against the bottom 298 of which bears a compressed spring 300, the other end of which bears against a pin 302, carried by slide 38 and extending through a slot 304 in said tie into 15 the bore 296 (see Fig. 6). This compression spring 292 normally urges slide 38 to the left as viewed in Fig. 5, thereby retaining roller 280 of arm 282 in permanent engagement with the cam disc 278. It can be understood from all the foregoing 20 that the slide 38 is positively moved to the right as viewed in Fig. 5 by the cam disc 278, and that this slide is moved to the left by the compression spring 300 under the control of cam disc 278. 25 The cam shaft 48 is driven by the earlier mentioned electric motor 50 in a manner to be described presently. This motor 50 is provided with any suitable reduction gearing 310, the slow shaft of which carries a small pinion 312 which 30 is in permanent mesh with a larger gear 314, mounted on a stub shaft 316 which is in axial alignment with cam shaft 48 and suitably journaled in a bearing bracket 46a on the lathe bed. Motor 50 is preferably continuously driven, 35 wherefore the stub shaft 316 is also continuously driven. Mounted on this stub shaft 316 is the driving half of the earlier mentioned clutch 52, the driven half of which is mounted on the cam shaft 48. This clutch may be of any suitable 40 type, and is preferably a friction clutch which is engaged or disengaged by axial movement of a clutch shifter 318, having an annular groove 320 receiving the anti-friction rollers 322 of a shifter fork 324 which is mounted on a shaft 326. This 45 shaft 326 is suitably journaled in the lathe bed 20 and extends to the front thereof where it carries a hand lever 328 for manipulation of said shaft and clutch. Also mounted on shaft 326 is an arm 330, carrying an anti-friction roller 332 50 which is adapted to cooperate with the periphery 334 of a disc-like extension 336 of the driven clutch half 338. Roller 332 is normally urged into engagement with the disc periphery 334 by means of a tension spring 340 which, as best 55 shown in Figs. 1 and 4, is secured to an arm 342, which is in turn mounted on shaft 326 near the hand lever 328. The disc periphery 334 is provided with a sole detent 344 into which the cam roller 332 will drop and cause disengagement 60 of the clutch 52 at the end of one complete revolution of the cam shaft 48. To start a new revolution of said cam shaft, the operator of the machine manipulates handle 328 against the tension of spring 340, thereby causing withdrawal 65 of cam roller 332 from the detent 344 and engagement of the clutch as can be readily understood. With the start of the cam shaft on a new revolution, the detent in the disc periphery 334 moves out of alignment with cam roller 332. After such disalignment of the 70 detent 344, the operator may release handle 328 because the cam roller now rides on the periphery 334 and thus maintains the clutch in engagement until after one complete revolution of 75 cam shaft 48 the detent 344 realigns with the

cam roller 332 and permits disengagement of the clutch. Hence, the operator merely has to engage the clutch 52 and pay no attention whatever to the disengagement thereof, thus enabling him to closely inspect finished armatures without haste. 5

Stoppage of chuck driving motor

In the present instance the chuck driving motor 28 is preferably a three phase motor, deriving its power source from any suitable supply, indicated by the power lines 350 in Figs. 14 to 16 inclusive. A conventional switch 352 is so connected between the motor and the power lines as to reverse the phase order and to open 15 the motor circuit. In Fig. 14 the switch 352 is shown in a position in which the motor 28 rotates the chuck in the proper direction for performing a turning and abrading operation upon the commutator of an armature. Fig. 15 shows 20 the switch 352 in reversing position, causing a braking action on the motor 28 and a subsequent momentary reversal of the motor. Fig. 16 discloses the switch 352 in open position. Therefore, Fig. 16 shows the motor circuit while the 25 machine is at rest. As best shown in Figs. 7 and 14, the rotor shaft 70 of motor 28 carries a small pulley 356 which by a suitable belt 358 drives a larger pulley 360. Rotatable together with pulley 360 coaxially thereof is a disc 362 which is 30 partly embraced by a band 364 of any suitable friction material. This friction band is secured to the opposite ends of a lever 366 which is pivotally mounted at 368 and carries a contact 370 and a stop 372. Cooperating with stop 372 is a 35 stationary stop 374, and cooperating with contact 370 is a stationary contact 376. Lever 366, contacts 370, 376 and stops 372, 374 may conveniently be termed a switch 367. Contact 370 is connected by a lead 371 to one contact 378 of any 40 conventional switch 379, having another contact 380 and a shiftable arm 382, carrying a contact 384 which may be engaged with either contact 378, 380. Contact 380 is connected by a lead 386 to the forward winding 388 of a solenoid 45 390, having a reverse winding 392 and a core 394 which may be actuated by either winding and is drivingly connected to the switch 352 by means indicated at 396. The reverse winding 392 is connected to contact 376 by a lead 398, and 50 both windings 388, 392 are connected to one of the power lines 350 by a lead 400. The conductive switch arm 382 is connected to another power line 350 by a lead 402. The switch arm 382 is linked at 404 to the arm 342 on shaft 326 55 (see also Fig. 1). Therefore, upon engagement of clutch 52 by manipulation of handle 328 in the earlier explained manner, the switch arm 382 is shifted from the position shown in Fig. 16 to that shown in Fig. 14, thereby closing the forward energizing circuit of the solenoid 390 through intermediation of lead 400, forward winding 388, lead 386, the engaged contacts 380 and 384, switch arm 382 and lead 402. Such 60 energization of the solenoid causes a shifting of the switch 352 from the open position in Fig. 16 to that shown in Fig. 14, in which the motor 28 is energized for forward rotation. Immediately after the motor 28 starts to rotate forwardly, lever 366 is rotated from the position shown in Fig. 16 to that shown in Fig. 14 in which contact 370 engages contact 376. This is accomplished due to the frictional engagement of band 364 with the disc 362 which is driven by motor 28 in the earlier explained manner. Of course, 65

after the contacts 370, 376 are in engagement with each other, the band 364 will merely slide on the disc 362, thereby frictionally maintaining the contacts in engagement. These contacts 5 370, 376 form part of the reverse energizing circuit of the solenoid 390, but fall short of closing the same because the contacts 384 and 378, forming also part of said reverse circuit are as yet open. Hence, during one complete revolution of 10 the cam shaft 48 during which a turning and abrading operation take place, the forward energizing circuit of the solenoid is kept closed due to the link connection 404 between the switch arm 382 and the arm 342 on shaft 326. As already explained, the clutch 52 is automatically 15 disengaged after one complete revolution of cam shaft 48, and such clutch disengagement is accompanied by a slight rocking of shaft 326 and arm 342 in such direction that the link 404 is 20 shifted in the direction of arrow 420 in Fig. 14. Such shifting of link 404 results in a switching of arm 382 from the position shown in Fig. 14 to that shown in Fig. 15, in which contact 384 engages contact 378 and closes the reverse energizing circuit of the solenoid 390. Consequently 25 the core 394 and the switch 352 are then shifted from the position shown in Fig. 14 to that shown in Fig. 15, resulting in a braking action on the motor 28 and subsequent momentary reversal of 30 the same. However, as soon as the motor 28 starts to rotate in the reverse direction, disc 362 rocks the lever 366 from the position shown in Fig. 15 to that shown in Fig. 16 due to frictional engagement of said disc with the band 364. 35 Such rocking of lever 366 naturally results in immediate disengagement of contacts 370, 376 and consequent opening of the reverse energizing circuit of the solenoid 390. The solenoid core 394 is connected to two tension springs 422 40 which normally tend to maintain said core in the balanced position shown in Fig. 16 in which the switch 352 is in open position. The switches 352, 379 and 367 may be conveniently housed in suitable boxes 500, 502, and 504, respectively, 45 which are mounted in any suitable manner on the lathe bed 20.

Mode of operation

With particular reference to the cam chart 50 shown in Fig. 17 the mode of operation of the present machine will be briefly reviewed hereafter. After the deposition of an armature 55 in the chuck and tail stock of the machine, the operator of the machine manipulates the hand lever 328, thereby engaging clutch 52 and thus causing one revolution of shaft 48 and the cams carried thereby. Such manipulation of hand lever 328 by the operator also starts the chuck driving motor 28. While the machine is at rest, 60 the transport 24 and slide 38 assume the position shown in Fig. 4. Immediately after shaft 48 starts on its one revolution, the cam drum 262 causes movement of transport 24 such that the cutting tool 40 moves into the dot-and-dash position shown in Fig. 4, and then immediately returns to the full line position shown in that figure. During such movement of the transport 24, represented by the lines *a*—*b* and *b*—*c* in the chart, the polygonal circumference of the commutator 42 is turned into cylindrical shape. It 65 follows from the chart that the reciprocation of the transport 24 takes place during approximately 205° revolution of the cam drum 262. Simultaneously with the arrival of the transport 70 in the position shown in Fig. 4, the slide 38 is

moved in the direction of arrow 60 in Fig. 4 by the cam disc 278 on shaft 48, until the abrasive strip portion 44b partly embraces the turned periphery of the commutator 42 in the manner disclosed in dot-and-dash lines in Fig. 10. Such 10 movement of the slide 38 is represented in the chart by the line *d*—*e* and takes place during approximately 50° further revolution of the cam shaft 48. While the abrasive strip portion 44b is progressing around part of the commutator periphery, the cam drum 262 causes slight movement of the transport 24 to the left as viewed in Fig. 4 in order to contact the abrasive strip with the entire length of the commutator periphery. Such movement of the transport is 15 represented by the line *f*—*g* in the chart. Immediately after the abrasive strip portion 44b reaches the left margin of the commutator as viewed in Fig. 4, the transport 24 returns into the position shown in that figure with the abrasive strip portion still in engagement with the commutator periphery. The return movement of the transport is represented in the chart by the line *g*—*h*. Somewhat prior to the return of the transport into the position shown in Fig. 20 25 4, slide 38 starts to move in the direction of arrow 62 in Fig. 4 as represented by the line *i*—*k* in the chart. Of course the abrasive strip is still in engagement with the commutator periphery when the transport returns into the position 30 shown in Fig. 4, but by that time embraces a smaller portion of the commutator periphery as can be readily understood. As soon as the slide 38 has returned into the position shown in Fig. 4, the one revolution clutch 52 is automatically 35 disengaged, and such disengagement of the clutch is responsible for an immediate braking action on the chuck driving motor 28 and subsequent momentary reversal thereof. As soon as the motor 28 is at rest, the centrifugally operated 40 chuck releases the armature shaft and the operator may then remove the finished armature from the machine and deposit a new armature therein. Having this done, the operator again manipulates hand-lever 328, starting the machine 45 on a new cycle of operation.

While the embodiment of the present invention as herein disclosed, constitutes a preferred form, it is to be understood that other forms might be adopted, all coming within the scope of 50 the claims which follow.

I claim:

1. In a machine of the character described, the combination of a support for an armature including a commutator; a transport movable longitudinally of the armature; a slide movable on the transport laterally of the armature; two tools mounted on the slide on opposite sides of the armature; means for moving the slide relative to the transport to cause engagement or separation between either tool and the commutator; and means for reciprocating the transport, said means being operated in such timed relation with the slide moving means as to reciprocate the transport through different distances during engagement of the different tools with the commutator. 55 60 65

2. In a machine of the character described, the combination of a support for an armature, said support including a rotary chuck for driving the 70 armature; a tool; rotary means for operating the tool; power driving means; a clutch for drivingly connecting the rotary means with the power driving means; an electric motor driving the chuck; means closing the motor circuit upon clutch en- 75

gagement and opening said motor circuit upon clutch disengagement and means braking the motor upon clutch disengagement.

3. In a machine of the character described, the combination of a support for an armature, said support including a rotary chuck for driving the armature; a tool; rotary means for operating the tool; power driving means; a clutch for drivingly connecting the rotary means with the power driving means; an electric motor driving the chuck; and means starting the motor upon clutch engagement and reversing and subsequently stopping the motor upon clutch disengagement.

4. In a machine of the character described, the combination of a support for an armature; a tool; rotary means for operating the tool; power driving means; a clutch for drivingly connecting the rotary means with the power driving means; a multi-phase motor for rotating the armature; and means closing the motor circuit upon clutch engagement and reversing the phase order to reverse the motor upon clutch disengagement.

5. In a machine of the character described, the combination of a support for an armature; a tool; rotary means for operating the tool; power driving means; a clutch for drivingly connecting the rotary means with the power driving means; a multi-phase motor for rotating the armature; and means closing the motor circuit upon clutch engagement and changing the phase order to reverse the motor and subsequently opening the reverse motor circuit upon clutch disengagement.

6. In a machine of the character described, the combination of a support for an armature; a tool; rotary means for operating the tool; power driving means; a clutch for drivingly connecting the rotary means with the power driving means; a multi-phase motor for rotating the armature; a normally open switch for closing the motor circuit and for changing the phase order to reverse the motor; means for maintaining the switch closed during clutch engagement; and means shifting the switch into phase changing position and subsequently releasing the switch upon clutch disengagement.

7. In a machine of the character described, the combination of a support for an armature; a tool; rotary means for operating the tool; power driving means; a clutch for drivingly connecting the rotary means with the power driving means; a multi-phase motor for rotating the armature; a normally open switch for closing the motor circuit and for changing the phase order to reverse the motor; means closing the switch upon clutch engagement and maintaining the switch closed during such clutch engagement; and means shifting the switch into phase changing position and subsequently releasing the switch upon clutch disengagement.

60 8. In a machine of the character described, the combination of a support for an armature; a tool; rotary means for operating the tool; power driving means; a clutch for drivingly connecting the rotary means with the power driving means; a multi-phase motor for rotating the armature; a normally open switch for closing the motor circuit and for changing the phase order to reverse the motor; means for maintaining the switch closed during clutch engagement; and means shifting the switch into phase reversing position upon clutch disengagement, said means being also responsive to reverse rotation of the motor to release the switch.

75 9. In a machine of the character described,

the combination of a support for an armature; a tool; rotary means for operating the tool; power driving means; a clutch for drivingly connecting the rotary means with the power driving means; a multi-phase motor for rotating the armature; a normally open switch shiftable into motor circuit closing position and into motor reversing position; a solenoid; a forward and a reverse circuit for energizing the solenoid, the forward circuit for shifting the solenoid core into motor circuit closing position and the reverse circuit for shifting the core into motor reversing position; another switch for selecting the forward or reverse circuit; said switch selecting the reverse circuit upon clutch disengagement; and means responsive to reverse running of the motor for opening the reverse circuit.

10 10. In a machine of the character described, the combination of a support for an armature; a tool; rotary means for operating the tool; power driving means; a clutch for drivingly connecting the rotary means with the power driving means; a multi-phase motor for rotating the armature; a normally open switch shiftable into motor circuit closing position and into motor reversing position; a solenoid; a forward and a reverse circuit for energizing the solenoid, the forward circuit for shifting the solenoid core into motor circuit closing position and the reverse circuit for shifting the core into motor reversing position; another switch shiftable to close either forward or reverse circuit, said switch being linked with the clutch to be shifted thereby; and means responsive to reverse running of the motor for opening the reverse circuit.

15 11. In a machine of the character described, the combination of a support for an armature; a tool; rotary means for operating the tool; power driving means; a clutch for drivingly connecting the rotary means with the power driving means; a multi-phase motor for rotating the armature; a normally open switch shiftable into motor circuit closing position and into motor reversing position; a solenoid; a forward and a reverse circuit for energizing the solenoid, the forward circuit for shifting the solenoid core into motor circuit closing position and the reverse circuit for shifting the core into motor reversing position; another switch shiftable to close either forward or reverse circuit, said switch being linked with the clutch to be shifted thereby; and a third switch in series with said reverse circuit, said switch being yieldingly closed during forward running of the motor and opened upon reverse running of the motor.

20 12. In a machine of the character described, the combination of a device holding the ends of a strip of abrasive sheet material stationary, said device including two spaced rolls over which the strip is guided and said strip being of such length as to be loose though guided over said rolls; and yielding strip tensioning means engaging a strip portion other than that between the rolls.

25 13. In a machine of the character described, the combination of a device holding the ends of a strip of abrasive sheet material stationary, said device including two spaced rolls over which the strip is guided and said strip being of such length as to be loose though guided over said rolls; a pivotally supported lever; a roller carried by the lever remote from its pivot support, said roller resting by gravity on a strip portion other than that between the first mentioned rolls, thereby substantially uniformly tensioning the

entire strip even though a work piece is forced against the strip portion between the first mentioned rolls and deflects said strip portion.

14. In a machine of the character described, the combination of a device for moving and directing a portion of a supply of abrasive sheet material into a certain disposition, said device including two identical pairs of cooperating feed rolls yieldingly engaging the beginning and end 10 of said portion which is of such length as to be loose between the pairs of feed rolls; means for simultaneously rotating at least one of each pair of feed rolls such that one pair thereof draws a length of material from the supply and feeds it 15 toward the other pair of feed rolls and said other pair withdraws the same length of material away from said one pair of feed rolls; and means yieldingly tensioning the material portion between the pairs of feed rolls.
15. In a machine of the character described, the combination of a device for moving and directing a portion of a supply of abrasive sheet material into a certain disposition, said device including two spaced guide rolls over which said 25 portion is passed and two identical pairs of co-operating feed rolls yieldingly engaging the beginning and end of said portion which is of such length as to be loose though passing over the 30 guide rolls; means for simultaneously rotating at least one of each pair of feed rolls such that

one pair thereof draws a length of material from the supply and feeds it toward the guide rolls and said other pair of feed rolls withdraws the same length of material away from the guide rolls; a pivotally supported lever; a roller carried by the 5 lever remote from its pivot support, said roller resting by gravity on a part of the material portion other than that between the guide rolls, thereby substantially uniformly tensioning the entire portion even though a workpiece is forced 10 against the material between the guide rolls and deflects said material.

16. In a machine of the character described, the combination of a support for an armature including a commutator; a first carrier; a second 15 carrier mounted on the first carrier for movement laterally of the armature; two tools mounted on the second carrier on opposite sides of the armature; mechanism for moving the second carrier relative to the first carrier to cause engagement or separation between either tool and the commutator; and means for causing relative reciprocity between the support and first carrier longitudinally of the armature, said means being operated in such timed relation with the mechanism as to cause relative reciprocity through 20 different distances during engagement of the different tools with the commutator.
